COMBINED LUBRICATING AND COOLING UNIT

Thomas R. Thomas, New York, N.Y., assignor to Auto Research Corporation, Boonton, N.J., a corporation of Delaware

Filed July 7, 1958, Ser. No. 51,682

Term of patent 14 years

(Cl. D65—1)

FIG. 1

FIG. 2

FIG. 3

FIG. 1 is a front perspective view of a combined lubricating and cooling unit showing my new design; and FIG. 2 is a side elevational view thereof.

The rear of the article is substantially plain.

I claim:

The ornamental design for a combined lubricating and cooling unit, substantially as shown and described.
